United States Patent Office.

RICHARD KNOTT, OF SUISUN CITY, CALIFORNIA.

Letters Patent No. 90,559, dated May 25, 1869.

IMPROVEMENT IN STAKE-PULLER.

The Schedule referred to in these Letters Patent and making part of the same.

To all whom it may concern:

Be it known that I, RICHARD KNOTT, of Suisun City, county of Solano, State of California, have invented an Improved Stake-Puller; and I do hereby declare the following description and accompanying drawings are sufficient to enable any person skilled in the art or science to which it most nearly appertains, to make and use my said invention or improvements, without further invention or experiment.

The object of my invention is to provide an improved device for pulling stakes, and more especially for drawing the iron pins which are used for securing horse-powers to the ground; and it consists of a lever, having at one end a ring, with a hole through it sufficiently large to pass down over the stake. One side of this ring is formed into a clip, which is pivoted to the end of the lever. A bar of metal is also pivoted by a similar attachment near the end of the lever, forming a lever of the first class.

To more fully describe my stake-puller, reference is had to the accompanying drawings, and letters marked thereon, forming part of this specification, of which—

Figure 1 is a side view;

Figure 2 is a bottom view.

A is a bar of iron, to one end of which is loosely attached a ring, B.

The hole in this ring is large enough to allow an ordinary-sized stake to be easily passed through it.

A short bar, C, is pivoted to the lever, near the end to which the ring B is attached, and serves as a fulcrum.

The opposite end of the lever is made into a suitable form to be easily grasped by the hand.

To operate the device, the ring is first slipped down over the stake to be drawn, and the fulcrum, or bar C, placed upon some solid body, in a convenient position, when, by bearing down upon the opposite end or handle of the lever, the ring is turned sideways, causing it to bind against the pin on opposite sides and hold firmly.

If the handle of the lever is then forced down by applying sufficient power, the pin will be drawn partly out, when the ring may be again lowered, and the same operation performed until the pin is entirely drawn from the ground.

With this device I am able, by two or three simple movements, to draw a pin from the ground, no matter how firmly it may be driven, causing a great saving of time in removing horse-powers when it is necessary to draw stakes, as one man can operate the machine and store away the stakes while the horses are being removed from the power, leaving everything free to be taken up and transferred to any place desired.

Having thus described my invention,

What I claim, and desire to secure by Letters Patent, is—

In combination with the lever A, and its fulcrum, the ring B, pivoted at one side to the end of said lever, substantially in the manner and for the purpose set forth.

In witness whereof, I have hereunto set my hand and seal

RICHARD KNOTT. [L. s.]
